UNITED STATES PATENT OFFICE.

WILLIAM CHAPPELL, OF CHICAGO, ILLINOIS.

CHECK-VALVE.

SPECIFICATION forming part of Letters Patent No. 314,107, dated March 17, 1885.

Application filed March 6, 1884. (No model.)

To all whom it may concern:

Be it known that I, WILLIAM CHAPPELL, a citizen of the United States, residing at Chicago, in the county of Cook and State of Illinois, have invented a certain new and Improved Check-Valve; and I hereby declare the following to be a full, clear, and exact description of the same.

My invention is designed particularly for use with bath-tub and water-closet waste-pipes, where these are connected, to afford a back-water valve. It frequently happens that the large quantity of water which enters a closet soil-pipe does not pass off as fast as supplied, and seeks an outlet through the pipe leading to the bath-tub, introducing into the latter water mixed with matter of the water-closet. The connection also affords a means of escape by way of the bath-tub, for gases arising from the sewer. It is the object of my invention to obviate these difficulties; and to this end my invention comprises a check-valve of peculiar construction located within one waste-pipe leading to another waste-pipe, whereby the waste in the one shall pass without obstruction into the other, the passage remaining closed, however, when the flow is in the opposite direction.

In the drawings, Figure 1 is a longitudinal vertical section of a bath-tub and water-closet provided with my improvement; Fig. 2, a longitudinal vertical section of my improved valve; and Fig. 3 a plan view of a detail.

A is a bulb provided with a tubular extension, *t*, at one end, the opening at the opposite end being beveled, and provided with a flange, *s*, slanting in the direction of the opening, but bent at its upper and lower edges in opposite directions, to form right angles with the bulb A and extension *t*, as shown at *s'* in Fig. 1, and provided with bolt-holes.

A' is a straight tube, of narrower dimensions than the bulb A, and having the opening at one end beveled to coincide with the beveled opening in the bulb, being also provided with the flange *q*, producing an internal shoulder, and formed in the manner described of the flanges. The detail shown in Fig.

3 represents the device for forming the valve 50 B, being located for that purpose between the parts just described, and held between the flanges, the right angular portions of which assist in producing a tight joint, the parts being joined together by means of bolts passing 55 through the bolt-holes provided, as described, in the flanges *s* and *q*, and also in the valve B, as shown at *x* in Fig. 3.

The part B comprises a disk, preferably of rubber, of dimensions sufficient to cover the 60 adjacent openings in the bulb A and tube A' and the inner adjacent faces of the flanges *s* and *q*.

A flap, C, of oval shape, is cut, extending part way around the center of the disk, leaving it connected at its top to operate as a hinge. A portion of the material of the flap C is cut away around the edges to provide an opening, *y*, and leaving the flap of dimensions greater than those of the opening to the 70 tube A', but less than those of the opening to the bulb A. A plate of metal, *p*, affording a strengthening medium and a weight for the flap, is secured upon one face of the latter by means of a bolt, *o*, passing through the 75 flap and plate and nut *o'*.

It will be understood from the foregoing description of the construction that the flap C can be swung upon its hinge into the bulb A, being of dimensions smaller than the same, 80 but being larger than the opening of the tube A', it will, when forced toward the same, abut against its edges and close the entrance in that direction.

The connection with the bath-tub D is 85 made in a manner to permit free flow of the water from it through its waste-pipe *n* into the soil-pipe *m* of the water-closet E by opening the flap C into the bulb A. Nothing can pass in the opposite direction from the soil-pipe *m* on account of the barrier formed by the abutment of the flap C against the edge of the opening in the tube A' and the inner face of the flange *q*.

What I claim as new, and desire to secure 95 by Letters Patent, is—

A valve to be inserted in a waste-pipe leading from a bath-tub to a water-closet,

comprising in combination the following elements, viz: a bulb, A, provided at one end with a tubular extension, *t*, and with a flange, *s*, at the opposite end, a tube, A', of narrower dimensions than the bulb A, and provided with a flange, *q*, a disk, B, of pliable material, secured between the flanges *s* and *q*, which are secured together, and a flap, C,

formed by cutting part way around the center of the disk B and hanging at one end from the same, all being constructed and arranged to operate substantially as described.

WILLIAM CHAPPELL.
In presence of—
THOMAS A. BANNING,
DOUGLAS DYRENFORTH.
